UNITED STATES PATENT OFFICE.

AMEDEE MASSEY AND AARON BENSON, OF NORWICH, CONNECTICUT.

PICKER-STICK CHECK.

Application filed November 28, 1921. Serial No. 518,393.

To all whom it may concern:

Be it known that we, AMEDEE MASSEY and AARON BENSON, citizens of the United States, residing at Norwich, in the county 5 of New London and State of Connecticut, have invented new and useful Improvements in Picker-Stick Checks, of which the following is a specification.

Our present invention pertains to looms 10 and more particularly to looms of the "Dra- per" type, and it contemplates the provision of a check through the medium of which the picker stick is placed under tension during movements of the shuttle in the shuttle box. 15 The invention further contemplates a check that is simple and inexpensive in construction and one that is well adapted to withstand rough usage.

The invention in all of its details will be 20 fully understood from the following description and claims when the same are read in connection with the drawings accompany- ing and forming part of this specification, in which:

25 Figure 1 is a side elevation of our novel tension means as applied to a portion of a loom.

Figure 2 is a sectional view taken in the 30 plane indicated by line 2—2 of Figure 1 and showing the left hand tension means.

Figure 3 is a sectional view taken in the plane 3—3 of Figure 1 and showing the right hand tension means.

Figure 4 is a sectional view taken in the 35 plane indicated by line 4—4 of Figure 1 and showing the left hand tension means and its relation to its complementary picker stick.

Figure 5, is a sectional view taken in the 40 plane indicated by line 5—5 of Figure 1 and showing the relation of the right hand tension means and its complementary picker stick.

Similar numerals of reference designate 45 corresponding parts in all the views of the drawings.

The right and left hand picker sticks 1 as well as the picker 2 thereof are of the 50 ordinary well known construction and as re- illustrated are properly positioned with re- spect to the loom lay A. Mounted on and adapted to move with respect to the lay within the box 4, is the shuttle 3.

Our novel left hand tension 5 is bolted or 55 otherwise secured to the lay A and adapted

to be secured in adjustable manner thereto. It will be manifest that the tension means is adapted for connection to various styles of lays as the case may be.

The tension means 5 comprises a body 60 provided with the bent end portions 8 that abut the lower surface of the lay and assist in retaining the body 5 in rigid manner on the lay A. Formed integral on the portion 5 is a hanger 7 that is bent parallel with respect to the bent end portions 8, at its lower end as indicated by 9.

The construction so far set forth is dupli- 70 cated on the opposite side of the lay as shown in Figure 4 and the two sections 5 are bolted to the lay by the one bolt 6. Pro- vided on the bent portion 9 of hangers 7 are orifices 9^a through which pass bolts or other means 10 and the said bolts also enter 75 parallel arms 11 that extend beyond the outer limit of motion of the picker stick and secured at their outer ends to each other by the bolt 12.

Interposed between the parallel arms 11 on the bolt 12 are washers 12' of leather 80 or other suitable material that receives the thrust and check the movement of the picker stick.

The tension members 11 are formed of 85 wood or other suitable material and hence the constant thrust of the picker stick will subject the tension members to strain be- yond their ability to withstand the same.

Moreover the construction of the tension 90 means and the washer interposed on the bolt 12 will assist in materially forcing in a quick manner the picker stick to cause same to rebound to the right after striking the washers.

Secured on the opposite end of the lay is 95 the right hand tension means that comprises the body portion 13 bolted or otherwise ar- ranged on the lay as indicated by 14 and the body portion 13 is provided with the bent ends 16 that bear on the underside of 100 the lay for the same purpose as the portions 8 of member 5.

The body portion 13 is provided with the integral hanger portion 15 having a lower bent end 17 provided with the orifice 18 that 105 receives a bolt 19 which in turn passes through one end of the parallel arms 20 of wood, or other similar material that are identical in construction to arms 11, above referred to. Arranged parallel with arms 110

20 are arms 21 and said arms 20 and 21 are secured at one end to each other by bolt 22.

Interposed on the bolt 22, between the series of arms 20 and 21 are washers 12' of leather or suitable cushioning material adapted to receive the thrust of the picker stick and secured to the free ends of arms 21 is a head portion that is held in proper position by means of the bolt 24.

10 A bolt for the purpose of reinforcing the head passes through as indicated by 23.

In the practical use of the invention it will be manifest that the outward thrust of the picker sticks against the washers of the 15 bolts is to limit the motion of the sticks during operation of the loom. It will also be seen that said washers will assist in causing a quick rebound of the picker sticks and because of the fact that the arms 11-20 and 21

20 are formed of a resilient wood or other suitable material the strain on the washers will be materially reduced and perfect operation of the picker sticks assured.

Manifestly the construction of our novel 25 tension means and the substitution of the wooden arms for the well known leather strap at present in use, assures a longer life and even and steady operation of the loom.

Having described our invention, what we

claim and desire to secure by Letters-Patent, 30 is:

1. In check mechanism, the combination of a loom, a body portion having a head secured to the loom, parallel spaced arms secured to the body, a bolt for securing the arms to each other, washers arranged on the bolt between the arms, a head secured on the arms and means for securing the head to said arms.

2. In means for the purpose set forth, the 40 combination of body members adapted to be secured to the lay of a loom, downwardly depending portions secured to the body members, abutments formed on the body members, arms adapted to receive a picker stick therebetween, hangers depending from the body members, arms secured to the hangers, and a head secured to the arms.

In testimony whereof we have hereunto set our hands in presence of two subscribing 50 witnesses.

AMEDEE X MASSEY.
mark
AARON BENSON.
